United States Patent Office.

WILLIAM M. BLEAKLEY, OF VERPLANK, NEW YORK.

Letters Patent No. 95,873, dated October 19, 1869.

IMPROVEMENT IN CAN-OPENERS.

The Schedule referred to in these Letters Patent and making part of the same.

To all whom it may concern.

Be it known that I, WILLIAM M. BLEAKLEY, of Verplank, in the county of Westchester, and State of New York, have invented a new and improved Can-Opener; and I do hereby declare that the following is a full, clear, and exact description thereof, which will enable others skilled in the art to make and use the same, reference being had to the accompanying drawing, forming part of this specification.

Figure 1 represents a side view of my improved can-opener.

Figure 2 is a plan or top view of the same.

Similar letters of reference indicate corresponding parts.

This invention relates to a new implement for opening sheet-metal cans, and is arranged to cut out larger or smaller pieces, as may be desired.

The invention consists in the combination of two levers, which are pivoted together, the pivot carrying a hook, which is forced into the can, and each lever having a projecting blade, one for holding one lever in place, and the other for cutting the metal.

The blades or prongs are adjustable on the levers, and allow thereby the adaptation of the implement to larger or smaller cans.

A B are two levers or bars, made of metal, or other material of suitable length. They are, at one end, connected by a pivot, a, which terminates below the lower bar B in a hook, b, as shown.

On the bar B is secured a downward-projecting prong or blade, C, which is fastened by a screw and

nut, as shown, or otherwise, and which can be longitudinally adjusted on the bar.

On the bar A is fastened a downward-projecting cutter, D, set transverse to the bar, and secured in a similar manner as the prong C, so that it can be longitudinally adjusted.

In order to effect the adjustment, the bar may either be slotted or perforated, or the shanks of the prong and cutter may embrace them.

The operation is as follows:

The hook is first forced into the centre of the piece to be cut out. The prong C is then, while A and B are held together, forced into the metal, and locks the bar B, producing thereby a stationary centre or pivot. The cutter is, at the same time, also forced into the metal, and the lever A swung around the pivot.

By attaching a small fixed cutter to the bar B, the piece can be entirely cut out, while, otherwise, the blade D cannot cut under the bar B.

Having thus described my invention,

What I claim as new, and desire to secure by Letters Patent, is—

A can-opener, composed of the levers A and B, which are pivoted together by a hook, and which carry respectively, the adjustable cutter D and the adjustable prong C, substantially as herein shown and described.

WM. M. BLEAKLEY.
